(57) CLAIM

The ornamental design for a combination disposable lighter holder and bottle cap opener with clip, as shown and described.

DESCRIPTION

FIG. 1 is a top, rear and right-side perspective view of a combination disposable lighter holder and bottle cap opener with clip embodying our new design, illustrating an exemplary disposable light in phantom;

FIG. 2 is a left-side elevational view thereof;

FIG. 3 is a right-side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The phantom line showing of a disposable lighter in FIG. 1 is for illustrative purposes only and forms no part of the claimed design.
